FIG. 1.

FIG. 2.

Inventor

WILLIAM T. JONES

By Campbell Bunting, First Seales
his Attorney

UNITED STATES PATENT OFFICE

168,511

CRUCIFIX

William T. Jones, Scranton, Pa., assignor to Consolidated Molded Products Corporation, Scranton, Pa., a corporation of Delaware

Application June 24, 1952, Serial No. 20,332

Term of patent 14 years

(Cl. D45—16)

To all whom it may concern:

Be it known that I, William T. Jones, a citizen of the United States, residing at Scranton, in the county of Lackawanna and Commonwealth of Pennsylvania, have invented a new, original, and ornamental Design for a Crucifix, of which the following is a specification, reference being had to the accompanying drawing, forming part thereof.

Fig. 1 is a front elevational view of a crucifix showing my new design; and

Fig. 2 is a side elevational view thereof.

I claim:

The ornamental design for a crucifix, as shown.

WILLIAM T. JONES.
